DESIGN FOR A CHARGER CLIP OR THE LIKE

Salvatore Giordano, South Ozone Park, N. Y., assignor to Frank J. Quigan, Inc., Maspeth, Long Island, N. Y., a corporation of New York

Application October 28, 1942, Serial No. 108,629

Term of patent 14 years

To all whom it may concern:

Be it known that I, Salvatore Giordano, a citizen of the United States, residing in South Ozone Park, Long Island, county of Queens and State of New York, have invented a new, original, and ornamental Design for a Charger Clip or the like, of which the following is a specification, reference being had to the accompanying drawing, forming a part thereof.

In the drawing,

Fig. 1 is a plan view of a charger clip or the like, showing my new design,

Fig. 2 is a front elevational view thereof, and

Fig. 3 is a rear elevational view thereof.

I claim:

The ornamental design for a charger clip or the like, as shown.

SALVATORE GIORDANO.
